UNITED STATES PATENT OFFICE.

GEORGE GALLIGAN, OF HERRIN, ILLINOIS.

SELF-RETAINING SPIKE.

1,118,544.

Specification of Letters Patent. Patented Nov. 24, 1914.

Application filed March 21, 1914. Serial No. 826,327.

To all whom it may concern:

Be it known that I, GEORGE GALLIGAN, a citizen of the United States, residing at Herrin, in the county of Williamson and State of Illinois, have invented certain new and useful Improvements in Self-Retaining Spikes, of which the following is a specification.

The object of this invention is to provide 10 a self-retaining spike so that a driven spike will be held in the tie against movement upwardly from the position into which it has been driven.

It is a further object of the invention to 15 provide the spike body with a keyway or bore extending downwardly therein for the reception of a key, one or more dog bores, with dogs therein, being arranged for engagement by the key to be forced or projected from the spike body into the structure of the tie.

A still further object of the invention is to provide one or more dogs which are loosely disposed in the bores therefor, and 25 which are so proportioned with respect to the key as to be not only driven but held in a driven or projected position after the key has been forced downwardly into the spike body.

30 Other objects and features of the invention will be more fully described in connection with the accompanying drawing and will be more particularly pointed out and ascertained in and by the appended claims.

35 In the drawing:—Figure 1 is a view in elevation of my improved self-retaining spike with the key partially inserted. Fig. 2 is a sectional view thereof. Fig. 3 is a view similar to Fig. 2, showing the key driven into position. Fig. 4 is a fragmentary view of a portion of the key and one of the dogs showing the manner in which the dogs are projected by the key.

40 Like characters of reference designate 45 similar parts throughout the different figures of the drawings.

As illustrated, 1 designates a spike body provided on one end with a head 2, and on its opposite end with a wedge-shaped entering portion 3. The entering end 3 may be of any desired form in accordance with 50 conditions under which the spike is used.

I provide the spike body with a longitudinally extending keyway or bore 4, which 55 is shown extending downwardly through the head 2, toward the entering end 3,

throughout a portion of the length of the body 1. The upper end of the key bore 4, may be enlarged, as indicated at 5, and the lower end of the key bore 4 is shown chamfered, as indicated at 6. In cross-section, the key bore 4 may be cylindrical. A key 7, which is likewise shown cylindrical in cross-section, is proportioned to fit snugly in the bore 4 and the key is provided with a wedge-shaped lower end 8 shaped to abut against the chamfered lower end 6 of the bore 4. A head 9 may be provided on the key 7 to fit the enlarged upper end 5, of the bore 4.

I provide one or more dog bores 10 which intersect the key bore 4 and which extend laterally of the longitudinal axis of the spike body 1 in a manner to open at one of the sides of said body, as clearly shown in 70 Figs. 2 and 3. In the preferred construction, the dog bores 10 are at right angles to the key bore 4 and the lowermost dog bore 10 is disposed above the lower end of the bore 4. A dog 11, is provided for each dog 80 bore 10, to be projected from one side of the spike body 1 when the key 7 is driven home.

The parts are so proportioned, in the construction shown, that when the dogs 11 are 85 in a retracted position, their outer ends, which may be conical, as indicated at 12, will lie substantially flush with the side 13 of the spike body, and their inner ends will abut one portion of the key bore 4, as clearly 90 shown in Fig. 2. This will limit retraction of the dogs 11 into the spike body 1 to just the necessary extent so as to bring the conical ends 12 at least flush with the side 13, without any lost motion or useless play in 95 projecting the dogs 11 after the spike is driven. I may if desired, round the inner ends of the dogs 11, as indicated at 14 to perform the dual function of fitting the bore 4 transversely thereof, and providing entrance ways for the wedge end 8 of the key 7, when the latter is driven down.

I deem it a special and important feature of this invention that the key 7, when driven 105 home, is driven downwardly past and beyond the lowermost dog so that the key will not only function to project the dogs into the body of the tie, from the spike body, as shown in Fig. 3, but will also lock the dogs and hold them in such projected position.

110 By means of the structure shown, all niceties of fit are avoided and machined

parts are not necessary as the bores can be cored in the spike and the key 7 and dogs 11 can be rough forgings if desired. Furthermore, reliance is not placed upon fulcrum juncture of the dog or dogs with the spike to take the strain imposed by the rail in lifting the spike, as the dogs have a most effective structural engagement with the structure of the spike body in order to take 10 the strain.

It is believed that the device of my invention will be clearly understood from the foregoing description and while I have herein shown and described one specific form of 15 my invention, I do not wish to be limited thereto except for such limitations as the claims may import.

I claim:

1. In a self-retaining spike, a spike body 20 provided with a penetrating end and having a key bore extending longitudinally through the body portion, said body having a dog bore intersecting the key bore and extending through to one side of the body, a dog 25 mounted in said dog bore to have endwise sliding movement in a direction at right angles to the line in which the spike is driven, and a key adapted to be driven into said key bore after the spike has been seated 30 and to cause endwise extension of said dog and penetration thereof into the member in which the spike is embedded.

2. In a self-retaining spike, a spike body provided with a longitudinally extending 35 key bore and a dog bore intersecting the key bore to extend at right angles thereto and opening to one side of the spike body, a retaining dog loosely and slidably disposed in the dog bore to be capable of longitudinal movement in the direction of the 40 extent of the dog bore, and a key adapted to be driven into the key bore to project the dog endwise from one side of the spike body.

3. In a self-retaining spike, a spike body 45 provided with a key bore extending longitudinally therein and of substantially cylindrical cross-section, said body having a cylindrical dog bore intersecting the key bore and opening at one side of the spike body, a 50 cylindrical dog loosely and slidably mounted in the dog bore and having a rounded end adapted to fit against the key bore, and a key of circular cross-section fitting the key bore and having a wedge-shaped end for 55 projection of the dog from one side of the spike body, said key being of sufficient length to be driven into engagement with

and downwardly beyond said dog to first project and then lock the dog in a projected position.

4. In a self-retaining spike, a spike body provided with a key bore extending longitudinally thereof and a dog bore above the lower end of the key bore intersecting the same and extending at right angles thereto to open at one side of the spike body, a dog loosely and slidably mounted in said dog bore adapted to be retracted into flush relation with one side of the spike body and into engagement with the key bore when the spike is driven and capable of movement to an extended position in line with the extent of said dog bore, and a key adapted to be driven into the key bore against the inner end of said dog and beyond the same to first project and then lock the dog in a projected position.

5. In a self-retaining spike, a spike body provided with a longitudinally extending bore and a plurality of dog bores formed 80 to intersect the key bore at right angles and to open at one side of the spike and disposed above the lower end of the key bore, a dog loosely and slidably mounted in each dog bore to be capable of endwise movement therein, and a key adapted to be driven downwardly in the key bore into successive engagement with and beyond the lowermost dogs and each of said dogs provided with a rounded end to engage with the key as 90 driven into the key bore and to bear frictionally against this key when in its seated relation to lock the key in place.

6. In a self-retaining spike, a spike body provided with a longitudinally extending 95 key bore and a dog bore at right angles thereto and intersecting the key bore and opening at one side of the spike body, a cylindrical dog loosely and slidably mounted in the dog bore and adapted to be retracted into the key bore to be capable of endwise movement therein, and a key adapted to be driven into the key bore into engagement with and past the dog for projecting the latter outwardly from the spike 100 body in the direction of the length of said dog.

In testimony whereof I affix my signature in presence of two witnesses.

GEORGE GALLIGAN.
